Primary Examiner — Nicole C Shiflet(74) *Attorney, Agent, or Firm* — Cantor Colburn LLP(57) **CLAIM**

The ornamental design for an oven, as shown and described.

DESCRIPTION

FIG. 1 is a front perspective view of an oven, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an enlarged view of the encircled portion in FIG. 1.

The even-dash broken lines depict portions of the oven that form no part of the claimed design. The dot-dot-dash broken lines encircling the enlargement portion of the claimed design form no part of the claimed design.

1 Claim, 8 Drawing Sheets(56)
